Primary Examiner — David G Muller*(74) Attorney, Agent, or Firm* — Roberts Mlotkowski Safran Cole & Calderon, P.C.(57) **CLAIM**

We claim the ornamental design of a multi-barrel syringe applicator, as shown and described.

DESCRIPTION

FIG. 1 is a front perspective view of a multi-barrel syringe applicator;

FIG. 2 is a rear perspective view of a multi-barrel syringe applicator;

FIG. 3 is a front elevational view of a multi-barrel syringe applicator;

FIG. 4 is a rear elevational view of a multi-barrel syringe applicator;

FIG. 5 is a left-side elevational view of a multi-barrel syringe applicator, which is identical to the right-side elevational view, except that the plungers are reversed; and, FIG. 6 is a top plan view of a multi-barrel syringe applicator, which is a mirror image of the bottom plan view.
